ADJUSTABLE TUBE AND FOLDER FOR SEWING MACHINES

Ronald Boser, Glen Oaks, N. Y.

Application May 15, 1957, Serial No. 659,372

2 Claims. (Cl. 112—147)

This invention relates to a sewing machine attachment and, more particularly, to a tube for guiding tapes, strips of lace and similar flatware to position for stitching onto the cloth or other work piece.

An important object of the present invention is to provide a guide for tapes, strips of lace and the like with means for accommodating the guide tube to tapes and strips of material of varying widths.

Another object of the invention is to provide an adjustable guide tube for tapes, strips of lace and the like that is readily manipulated and that will not interfere with the passage of the tape, lace and the like.

A further object of the invention is to provide an adjustable guide tube that is simple in construction, efficient in operation and economical to manufacture.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a top plan view of a sewing machine attachment embodying one form of my invention, a strip of lace being shown in operative position therein.

Fig. 2 is a bottom plan view thereof, with the backing plate removed.

Fig. 3 is a top plan view of the backing plate of the attachment.

Fig. 4 is a sectional view taken on the plane of the line 4—4 of Fig. 2.

Fig. 5 is a sectional view taken on the plane of the line 5—5 of Fig. 2.

Fig. 6 is a plan view of the adjustable section of the tube.

Fig. 7 is a bottom plan view of a modified form with the backing plate removed and showing a tape in operative position.

Fig. 8 is a sectional view taken on the plane of the line 8—8 of Fig. 7.

Fig. 9 is a bottom plan view of another modified form of the invention with the backing plate removed and showing a strip of lace and a tape in operative position.

Fig. 10 is a sectional view taken on the plane of the line 10—10 of Fig. 9.

Fig. 11 is a sectional view taken on the plane of the line 11—11 of Fig. 9.

Referring in detail to the drawings, in Fig. 1 an attachment embodying my invention is shown on the bedplate 10 of a sewing machine. This attachment includes a front plate 11 and a backing plate 12. The backing plate is rectangular in shape and cast with a reduced central portion 13. The front plate 11 is preferably formed of sheet metal of substantially the same shape as the backing plate but of larger dimensions. The attachment is secured to the bedplate 10 by means of screws 14 passing through openings in the backing plate 12 at one side thereof. An

2

opening 15 is formed in the front plate at the side thereof in line with a screw 16 in the backing plate.

A guide, for the passage of a strip 17 of lace or the like to be stitched to a work piece (not shown), in the form of a flattened tube 18 of sheet metal, is secured to the rear surface of the plate 11 by soldering or in any other suitable manner. The guide tube 18 is positioned centrally of the plate and extends the length thereof. A bracket plate 19 soldered to one side of the tube midway 10 its ends and positioned flush with the outer surface of the tube is formed with an elongated slot 20 to receive the shank of a screw 21 through an aligned opening 22 in the front plate 11 for fastening the front plate to the backing plate and the attachment to the bedplate 10. An elongated flat narrow metal bar 23 is soldered along the opposite side of the tube 18 and is positioned flush with the outer surface of the tube 18 and bracket 19 and is closely spaced from the rear surface of the plate 11 providing a clearance 24 therebetween. The bar is formed 20 with an elongated slot 25 to receive the shank of a screw 26 through an aligned opening 26' in the front plate 11 for fastening the front plate to the backing plate and the attachment to the bedplate 10. When the front plate 11 is attached, the tube 18, bracket 19 and bar 23 are positioned in the reduced portion 13 of the backing plate.

In accordance with the present invention, the passage in the tube 18 through which the strip 17 of lace passes is made adjustable in width to accommodate strips of material, tapes and the like of different widths or sizes. 30 This is accomplished by cutting away or recessing the material of the tube 18 at one end thereof, as indicated at 27, its top end as viewed in Figs. 1 and 2, leaving a narrow extension 28 at one side thereof formed with a groove or trough 29 to guide one side edge of the strip of lace 35 17 in its passage outward of the tube.

Overlying the rear surface of the front plate 11 at one side thereof, there is a thin metal plate 30 pivoted to the bar 23 and swingable thereunder in the space or clearance 24. This plate comprises a narrow curved shank portion 31 formed at one end with a reduced portion upturned in the form of a lug 32 extending into an opening 33 formed in the end of the bar 23 and forming a pivot around which the plate 30 pivots. The other end of the shank portion terminates in an enlarged portion 34 having an 40 extended neck portion 35 and a head 36 supported by the neck portion. The head has a grooved or trough portion 37 complementary to the grooved extension 28 on the end of the tube 18, the grooved portion 37 and the grooved extension 28 facing each other when the plate 30 is in operative position. A finger piece or handle 40 is formed integrally with the plate 30 on its side opposite the enlarged portion 34 and extends outwardly of the adjacent side edge of the plate 11 whereby it can be conveniently grasped for moving the head 36 toward and away from the tube to adjust the width of the passage at this point. The finger piece 40 may be provided with a hole 41 to receive a device or tool for moving the plate 30. The shank of a screw 42 extending through the aligned opening 43 and 44 in the bar 23 and plate 11, 50 respectively, and through an elongated slot 45 in the enlarged portion 34 of the plate 30 limits the pivotal movement of said plate 30. An elongated narrow window 46 may be cut in the front plate 11 in the path of movement of the strip 17, and the wall of the tube 18 may be extended slightly and curved away from the bottom edge 55 of the front plate 11 as indicated at 47 in order to widen the clearance for the entrance of the strip 17.

Ordinary mechanism may be used for feeding the strip through the tube. In order to move the plate 30 to adjust the width of the passage, it is only necessary to loosen screw 42 and in order to hold the plate in adjusted moved position the screw is turned and tightened. It is believed

the operation of the invention will be apparent to those skilled in the art.

In the modified form of the invention shown in Figs. 7 and 8, the guide tube 18' tapers from a point approximately midway its ends to its bottom end as viewed in Fig. 7, the wider portion being at the bottom end where the tape or strip 17' enters the tube in flatwise condition. A blade or elongated plate 50 extends centrally of the tube 18' for folding the edges of the tape or strip 17' as it passes through the tube so that said tape or strip passes out of the tube with its edges in folded condition.

In all other respects, the form of invention shown in Figs. 7 and 8 is similar to the form shown in Figs. 1 to 6, inclusive, and similar reference numerals are used to indicate similar parts.

Referring now to the modification of the invention shown in Figs. 9 to 11, inclusive, this form combines the guide tube 18 of Figs. 1 to 6, inclusive, for guiding a strip 17 of lace, and the guide tube 18' of the form of Figs. 7 and 8 for guiding and folding simultaneously a tape 17' or the like, the tube 18' being superimposed on top of the tube 18. The bracket 19 and bar 23 are soldered to the outermost tapered tube 18'. The tape 17' is fed outwardly of the tube 18' in folded condition and the strip 17 outwardly of tube 18 of lace in flat condition.

The adjustment of the width of the passage for the strip 17 of lace is similar to the adjustment provided for the form of Figs. 1 to 6, inclusive. No adjustment is provided for the width of the passage for the tape 17'.

In all other respects, the form of invention shown in Figs. 9 to 11, inclusive, is similar to the form shown in Figs. 1 to 6, inclusive, and similar reference numerals are used to indicate similar parts.

While I have illustrated and described the preferred embodiments of my invention, it is to be understood that I do not limit myself to the precise constructions herein disclosed and that various changes and modifications may be made within the scope of the invention as defined in the appended claims.

Having thus described my invention, what I claim as new, and desire to secure by United States Letters Patent is:

1. An attachment for sewing machines comprising a backing plate with means for fastening the plate to the bedplate of a sewing machine, a front plate secured to said backing plate, said front plate having a fixed guide tube centrally thereof on its rear surface for guiding a flat strip of fabric toward a needle on the sewing machine, said tube being closed on all sides and being open at both ends, one end of said tube being recessed on one side thereof forming an extension with an inwardly facing groove therealong, said extension forming one side wall of the tube, and means for adjusting the width of the 10 guiding passage for the strip, said means including a plate pivoted to the front plate and separate from and swingable toward and away from the tube, said pivotal plate having a head with a groove therealong facing inwardly and adapted to face the groove in the extension of the 15 tube to form the other side wall of the tube.
2. An attachment for sewing machines as defined in claim 1, wherein a second guide tube is secured to and superimposed upon the first-named guide tube, said second guide tube having a flaring end opposite the recessed 20 end of the first-named guide tube, for receiving a strip of fabric in flatwise condition, a plate in said second-named guide tube extending centrally thereof for folding the edges of the strip during its passage through said second guide tube.
